UNITED STATES PATENT OFFICE.

JAMES PAULL, OF WELLSBURG, WEST VIRGINIA.

DESIGN FOR A GLASS RECEPTACLE.

SPECIFICATION forming part of Design No. 37,269, dated December 20, 1904.

Application filed November 7, 1904. Serial No. 281,809. Term of patent 14 years.

To all whom it may concern:

Be it known that I, JAMES PAULL, of Wellsburg, in the county of Brooke and State of West Virginia, have invented a new, original, and ornamental Design for Glass Receptacles, reference being had to the accompanying drawings, forming part of this specification, in which—

Figure 1 is a side elevation of a glass recep-

tacle, and Fig. 2 is a vertical section of the same.

I claim—

The ornamental design for a glass receptacle, as shown.

JAMES PAULL.
